CIRCUIT BREAKER

Maurice H. Hobbs and Robert C. Dickinson, Pittsburgh, and Raymond J. Idzkowski, Turtle Creek, Pa., assignors to Westinghouse Electric Corporation, East Pittsburgh, Pa., a corporation of Pennsylvania

Application January 17, 1951, Serial No. 206,446

7 Claims. (Cl. 200—162)

1

This invention relates to circuit breakers and more particularly to contact means and to a bumper for circuit breakers.

An object of this invention is to provide a circuit breaker having relatively movable contact means with means for preventing rebound of the movable contact upon closure of the contact means.

Another object of the invention is to provide a high-speed circuit breaker having relatively movable contact means embodying improved means for decelerating the moving contact and preventing rebound of the moving contact upon closure of said contact means.

The novel features that are considered characteristic of the invention are set forth in particular in the appended claims. The invention itself, however, both as to structure and operation, together with additional objects and advantages thereof, will be best understood from the following detailed description of one embodiment thereof when read in conjunction with the accompanying drawing.

In said drawing:

Figure 1 is a side elevational view of a circuit breaker embodying the principles of the invention.

Fig. 2 is an enlarged top plan view of the contacts shown in the closed position.

Fig. 3 is an enlarged fragmentary side elevational view of the contacts in the closed position.

Referring to Fig. 1 of the drawing, the circuit breaker comprises generally a back plate 11 upon which the breaker mechanism is mounted, stationary contact means 13, movable contact means 15, closing mechanism indicated generally at 17 and trip-means indicated generally at 19.

The stationary contact means 13 is rigidly mounted on the inner end of an insulating bushing 21 supported on and extending through the back plate 11. A rod 23 of conducting material extends through the bushing 21 and serves as a terminal to connect the stationary contact 13 in an electrical circuit. The movable contact means comprises a pair of spaced contact blades 25 pivotally mounted on a conducting member 27. The member 27 is rigidly mounted on the inner end of an insulating bushing 29 which is mounted on and extends through the back plate 11. A terminal rod 31 of conducting material is electrically connected to the member 27 and extends outwardly through the bushing 29.

The contact blades 25 are disposed one on each side of the member 27 and are pivoted on a pivot pin 33 extending therethrough. The contact

2

blades are operatively connected by means of a link 35 to one arm of a bell crank 37 the other arm of which is connected by means of a link 39 to an operating lever 41. The bell crank 37 is pivotally mounted on a bracket 43 secured to the back plate 11 and the operating lever 41 is pivotally mounted on a bracket 45 also secured to the back plate 11.

A spring 47 tensioned between a fixed part of the breaker and a pin 49 on the operating lever 41 biases the latter in a clockwise direction. The operating lever 41 is releasably restrained against the bias of the spring 47 by means of a pivoted latch 51 forming a part of the trip device 19. The latch 51 is biased by means of a spring 53 into latching engagement with a latch roller 55 carried on the free end of the operating lever 41. The latch 51 is pivoted on a pin 57 and is adapted to be actuated in a counterclockwise or unlatching direction by operation of a tripping electromagnet indicated generally at 59. The tripping electromagnet comprises an energizing winding 61, a fixed core member 63 and a movable armature 65 to which it attached a trip rod 67 extending upwardly through an opening in the core member 63 and adapted to engage a tail 69 of the latch 51 upon energization of the electromagnet.

The tripping electromagnet may be energized from any suitable source, for instance, in response to overload currents or by manually closing a suitable switch. When energized the electromagnet 59 attracts its armature 65 and thrusts the rod 67 upwardly to actuate the latch 51 to unlatching position whereupon the spring 47 moves the operating lever 41 sharply in a clockwise direction. This movement is transmitted through the link 39, bell crank 37 and the link 35 to move the switch blade 25 to the open circuit position in which they are shown at 25' in Fig. 1.

The closing means 17 comprises a closing solenoid including an energizing winding 71, a fixed core member 73 and a movable armature 75. The armature 75 is attached to a rod 77 which has its upper end pivotally mounted on the pin 49 thus connecting the armature 75 to the operating lever 41. When the latch 51 releases the operating lever 41 and this lever is moved to the open position to effect opening of the contacts 25—13, the armature 75 of the closing solenoid is moved upward to its unattracted position.

The circuit breaker is operated to the closed position by energization of the closing solenoid which may be effected in any suitable manner either manually or automatically. When energized the closing solenoid attracts its armature

75 and moves the operating lever 41 counterclockwise to its latched position (Fig. 1). During this movement the lever 41 acts through the link 39, the bell crank 37 and the link 35 to move the contact blades 25 to the closed position.

Referring to Fig. 2 of the drawing, it will be observed that in the closed position the contact blades 25 engage opposite sides of the stationary contact 13. The contact blades 25 are provided with facing elongated contacts 79 disposed along their leading edges for engaging the stationary contact 13 with a wiping action. In the open position the contact blades 25 are spaced apart by means of a spacer 81 disposed therebetween and mounted on a bolt 83 which extends through openings in the switch blades. The bolt 83 is provided with a head 85 on one end and the other end threadedly engages a nut 87. Normal contact pressure is provided by means of a spring 89 compressed between the head 85 of the bolt 83 and the adjacent contact blade 25.

Rapid deceleration of the contact blades by striking a rubber stop at the end of a high-speed closing operation causes contact bounce or rebound. The rebound forces are transmitted to the contact spring and sets up vibrations causing momentary loss of spring pressure and consequent short separation of the contacts with the resultant arcing and burning of the contacts. To overcome this difficulty there is provided an improved stop means which not only prevents contact bounce but increases the contact pressure at the end of the closing operation.

The stop means comprises a pair of resilient stop members 91 (Figs. 2 and 3) disposed one on each side of the stationary contact 13 and secured thereto by means of bolts 93 and nuts 95. The resilient stop members 91 are preferably made of rubber or a rubber-like material. The bolts 93 extend through openings in the stop members 91, the stationary contact 13 and plates 97 disposed one on the outside of each of the stop members 91. The inner edges of the stop members 91 are beveled as at 99 to cooperate with the beveled edges 101 of the contact blades 25.

When the beveled edges 101 of the contact blades 25 engage the beveled edges 99 of the stop members 91 during the latter part of the closing operation the resiliency of the stop members 91 quickly decelerate the closing movement of the contact blades 25 and the cooperating beveled edges of the stop member and the contact blades forces the contact 79 against the stationary contact 13 thus increasing the contact pressure and preventing any tendency of the contact blades 25 to rebound or bounce.

The rubber stop members and the contact blades are so arranged that the deceleration is a product of both the elasticity of the rubber and the friction between the contact blades and the stop members. The deceleration occurs over an appreciable distance, hence, with a lesser rate and a lesser rebound force. The beveled edges of the contact blades and of the rubber stop members are made so that the mechanical advantage of the wedge is used to transmit a lateral force to aid the contact spring force in maintaining contact pressure while the contact blades are being decelerated.

Having described the invention in accordance with the patent statutes, it is to be understood that various changes and modifications may be made in the particular embodiment disclosed without departing from some of the essential features of the invention.

We claim as our invention:

1. In a circuit breaker comprising rigid stationary contact means, movable contact means, a spring on said movable contact means normally providing contact pressure in the closed position of said contact means, operating mechanism for moving said movable contact means to closed position, a fixed member of resilient material engageable by said movable contact for decelerating the closing movement of said movable contact and a portion of said fixed resilient member co-operating with said movable contact means to increase the contact pressure.
2. In a circuit breaker comprising rigid stationary contact means, movable contact means having a beveled portion thereon, spring means on said movable contact means normally providing contact pressure in the closed position of said contact means, operating means for moving said movable contact to the closed position, a fixed member of resilient material engageable by said movable contact means for decelerating the closing movement of said movable contact means, and said resilient member having a beveled portion engageable by the beveled portion of said movable contact means to increase the contact pressure near the end of the closing operation.
3. In a circuit breaker comprising rigid stationary contact means, movable contact means having a beveled portion thereon, a spring mounted on said movable contact means normally providing contact pressure in the closed position of said contact means, a member of resilient material fixedly mounted on said stationary contact means for decelerating the closing movement of said movable contact means, said resilient member having a portion forming an acute angle relative to said stationary contact means, and said beveled portion of said movable contact means coacting with said angular portion of said resilient member during the latter part of the closing operation to prevent rebound of said movable contact means and to increase the contact pressure.
4. In a circuit breaker comprising a single rigid stationary contact member, movable contact means comprising a pair of spaced movable contact blades adapted to engage opposite sides of said stationary contact member, spring means on said movable contact blades normally providing contact pressure between both of said contact blades and said stationary contact member in the closed position of said contacts, operating mechanism for moving said movable contact blades to open and closed positions, resilient stop means comprising a pair of members of resilient material fixedly mounted on said stationary contact member and disposed one on each side of said stationary contact member for decelerating the closing movement of said contact blades, each of said resilient members having a surface facing said stationary contact member and disposed at an angle thereto, and beveled surfaces on said contact blades cooperating with said surfaces on said resilient members during a closing operation to prevent rebound of said contact blades and to increase said contact pressure.
5. In a circuit breaker comprising a rigid elongated stationary contact member, movable contact means comprising a pair of contact blades having beveled portions thereon, elongated contacts on said contact blades disposed to engage opposite sides of said stationary contact member, spring means on said movable contact blades

providing contact pressure in the closed position of said contacts, operating mechanism for said movable contact means, resilient stop means comprising a member of resilient material fixedly mounted on said stationary contact member disposed one on each side thereof for decelerating the closing movement of said contact blades, each of said resilient members having a beveled surface for cooperating with the beveled edge of the corresponding contact blade during a closing operation to prevent rebound of said contact blades and to increase the contact pressure.

6. A circuit breaker comprising a rigid stationary contact member, movable contact means comprising a pair of spaced contact blades adapted to engage opposite sides of said rigid stationary contact member, a spring mounted on said movable contact blades for normally providing contact pressure between both of said movable contact blades and said rigid stationary contact member in the closed position of said contacts, operating mechanism for moving said movable contact blades to open and closed positions, stop means comprising blocks of resilient material mounted on said rigid stationary contact member on opposite sides thereof engageable by said contact blades for decelerating the closing movement of said contact blades, each of said blocks of resilient material having a surface facing the corresponding side of said rigid stationary contact and disposed at an acute angle relative thereto, and angular surfaces on said contact blades disposed to engage the angular surfaces

on said resilient blocks in a manner to force said contact blades against the sides of said rigid stationary contact member to prevent rebound of said contact blades and to increase the contact pressure.

7. In a circuit breaker comprising a rigid stationary contact member, a movable contact having a beveled portion thereon, a spring providing normal contact pressure in the closed position of said contact, stop means comprising a block of resilient material mounted on said rigid stationary contact member for decelerating the closing movement of said movable contact, said block of resilient material having a portion forming an acute angle relative to said rigid stationary contact member, and said beveled portion of said movable contact coacting with said angular portion of said resilient block during the latter portion of the closing operation to increase the normal contact pressure provided by said spring.
